UNITED STATES PATENT OFFICE

102,096

DESIGN FOR A GLASS TUMBLER

Donald M. Smith, Jeannette, Pa., assignor to McKee Glass Company, Jeannette, Pa., a corporation of Pennsylvania

Application September 23, 1936, Serial No. 65,029

Term of patent 14 years

To all whom it may concern:

Be it known that I, Donald M. Smith, a citizen of the United States, residing at Jeannette, in the county of Westmoreland and State of Pennsylvania, have invented a new, original, and ornamental Design for a Glass Tumbler, of which the following is a specification, reference being had to the accompanying drawing, forming part thereof, in which Figure 1 is a side elevational view of a glass tumbler showing my new design, and Figure 2 a vertical cross-sectional view thereof.

I claim:

The ornamental design for a glass tumbler as shown.

DONALD M. SMITH.
